UNITED STATES PATENT OFFICE.

ALFRED P. HIRSCHFELD, OF MERIDEN, CONNECTICUT, ASSIGNOR TO BRADLEY & HUBBARD MFG. CO., OF MERIDEN, CONNECTICUT, A CORPORATION.

SHADE HOLDER.

Application filed October 30, 1923. Serial No. 671,650.

To all whom it may concern:

Be it known that I, ALFRED P. HIRSCHFELD, a citizen of the United States, residing at Meriden, in the county of New Haven and State of Connecticut, have invented a new and useful Improvement in Shade Holders; and I do hereby declare the following, when taken in connection with the accompanying drawings and the characters of reference marked thereon, to be a full, clear, and exact description of the same, and which said drawings constitute part of this application, and represent, in—

Fig. 1 a view in side elevation of one form which my improved shade-holder may assume, shown with a shade.

Fig. 2 an enlarged, broken view thereof, mainly in section, showing the socket-cover in elevation.

Fig. 3 a detached view, in elevation, of the socket-cover.

Fig. 4 a detached view, partly in elevation and partly in section, of the loose coupling-collar.

Fig. 5 a similar view of the shade-ring, by which the shade is supported and stabilized.

Fig. 6 a view corresponding to Fig. 2, but showing the adaptation of my improvement for the mounting of glass and similar shades.

My invention relates to an improvement in shade-holders of the class designed for application to the covers of standard electric lamp-sockets, the object being to produce, at a low cost, a simple, efficient, convenient and tasteful device, constructed with particular reference to stabilizing the connection between the socket cover and the shade.

With these ends in view, my invention consists in a shade-holder having certain details of construction and combinations of parts as will be hereinafter described and particularly pointed out in the claims.

In carrying out my invention, as shown in Figs. 1 to 5 inclusive, I employ a one-piece shade-ring comprising a mounting-flange 10, an upstanding, threaded sleeve 11 and a horizontal bearing-surface 12 extending inwardly from the upper edge of the said threaded sleeve. As shown, the said ring is fastened by soldering or otherwise directly to the flattened upper face of the upper edge of the annular band 13 of a skeleton shade-frame having a plurality of curved ribs 14, the lower ends of which are united by droop-

ing or festoon-like bands 15. By preference, the band 13, ribs 14 and bands 15 are cast in one piece. Into the spaces between them I preferably insert panels 16 of semi-transparent parchment paper, but my invention is limited to no particular form or type of lamp-shade.

The bearing-surface 12 of the shade-ring aforesaid will substantially correspond in diameter to the mouth or open end of a standard bell-shaped, metal socket-cover 17 herein shown as having an annular terminal flange 18 merging into a fillet 19, from which it is separated by a draft-shoulder 20, the said fillet merging into the body of the socket 17. It is not essential that the bearing-surface 12 and the edge of the flange 18 shall correspond in diameter, but only that they shall be sufficiently like in diameter to have full bearing of one upon the other for stabilizing the union between the shade-ring and the socket-cover, when they are drawn together by the coupling-collar, loosely mounted upon the said cover. This coupling-collar, as shown, consists of a threaded ring 21 adapted to be screwed upon the upstanding sleeve 11 of the shade-ring, and with a knurled operating or draft-ring 22, the outer edge of which is fastened to the threaded ring 21 and the inner edge of which is adapted to engage with the draft-shoulder 20 aforesaid. The coupling-ring as thus constructed is free to be lifted with respect to the socket-cover 17, by which, however, it will be retained in place.

In using my improved device, the parts are brought together so that the inwardly-turned edge of the open end or mouth of the socket-cover rests directly upon the bearing-surface 12 of the shade-ring, after which the said cover and shade-ring are firmly drawn together by screwing the coupling-ring down over the upstanding threaded-sleeve of the shade-ring, whereby the parts are not only firmly drawn together but also accurately centered, and whereby the union between the parts, effected by the threads of the sleeve 11 and ring 21 is stabilized by the bearing of the edge of the cover upon the bearing-surface 12.

In the modified construction shown by Fig. 6 of the drawings, the shade-ring is formed with an upstanding, threaded sleeve 23 corresponding to the sleeve 11 aforesaid and with a bearing-surface 24 correspond-

ing to the bearing-surface 12 aforesaid, but in this modified construction, the ring is not mounted upon a skeleton shade-frame but passed upward through an opening 25 in a glass shade 26, which rests upon a gasket 27 supported by a suspension-flange 28 formed at the lower end of the shade-ring and corresponding in position, though not exactly in form, to the fastening flange 10 of the ring shown in Fig. 5.

It will be apparent from the foregoing that the character of the shade may vary without departing from my invention, which is characterized by a shade-ring having an upstanding sleeve merging at its upper end into a horizontal bearing-surface, receiving and corresponding substantially in diameter to the socket-cover, the edge of the said cover and the said bearing-surface being firmly held in engagement by a coupling-ring loosely mounted upon the socket-cover. As shown, the coupling-ring is made in two pieces, but may as well be made in one.

I claim:

25 1. In a shade-holder, the combination with a shade-ring adapted to carry a lamp-shade having a threaded sleeve, and a bearing-surface extending inwardly from the edge thereof at a right angle thereto, of a bell-shaped, metal socket-cover adapted in diameter at its larger open end to rest directly upon the said bearing-surface and provided at said end with an annular draft-shoulder,

and a threaded coupling-collar loosely mounted upon the said cover and co-acting with the draft-shoulder thereof and with the threaded sleeve of the said shade-ring to seat the open edge of the said cover firmly upon the bearing-surface of the said shade-ring. 35

2. In a shade-holder, the combination with a skeleton, metal shade-frame, of a shade-ring fastened to the upper end thereof and comprising a mounting-flange, an upstanding threaded sleeve and a horizontal bearing-surface extending inwardly from the upper edge of the said sleeve at a right angle thereto, a bell-shaped, metal socket-cover adapted to be suspended from its upper end and at its lower end to bear directly upon the said bearing-surface and provided adjacent its lower end with an annular draft-shoulder, and a threaded coupling-collar loosely mounted upon the said cover and co-acting with the draft-shoulder thereof and with the threaded sleeve of the said shade-ring to seat the open edge of the said cover firmly upon the said bearing-surface. 40

In testimony whereof, I have signed this specification in the presence of two subscribing witnesses.

ALFRED P. HIRSCHFELD.
